[57] CLAIM

The ornamental design for a carton, as shown and described.

DESCRIPTION

FIG. 1 is a perspective view of a carton showing our new design;

FIG. 2 is a top plan view, with the top and bottom having identical plan views;

FIG. 3 is a side elevational view, with the carton having three identical sides; and,

FIG. 4 is a plan view of a blank for forming the carton in FIGS. 1, 2 and 3.

The broken lines shown on FIG. 4 represent fold lines.

1 Claim, 3 Drawing Sheets
